[57] CLAIM

The ornamental design for a planer apparatus, as shown and described.

DESCRIPTION

FIG. 1 is a front perspective view of a planer apparatus showing our new design with the pivotal tables thereof in an extended position;

FIG. 2 is a front elevational view of the planer apparatus of FIG. 1;

FIG. 3 is a rear elevational view of the planer apparatus of FIG. 1;

FIG. 4 is a top view of the planer apparatus of FIG. 1;

FIG. 5 is a bottom view of the planer apparatus of FIG. 1;

FIG. 6 is a left side elevational view of the planer apparatus of FIG. 1;

FIG. 7 is a right side elevational view of the planer apparatus of FIG. 1; and,

FIG. 8 is a rear perspective view of the planer apparatus of FIG. 1.

The broken line showing is for illustrative purposes only and forms no part of the claimed design.
